UNITED STATES PATENT OFFICE

109,048

DESIGN FOR A DISPLAY CONTAINER OR SIMILAR ARTICLE

Ernest M. Brogden, Orlando, Fla.

Original design application August 9, 1935, Serial No. D-58,050. Divided and this application January 26, 1937, Serial No. 67,296

Term of patent 14 years

To all whom it may concern:

Be it known, that I, Ernest M. Brogden, a citizen of the United States, residing at Orlando, county of Orange, State of Florida, have invented a new, original, and ornamental Design for a Display Container, or Similar Article, of which the following is a specification, reference being had to the accompanying drawing, forming a part thereof, and in which:

Fig. 1 is a top plan view of the article showing my design, and

Fig. 2 is a perspective view.

The design of my container comprises a tray or body portion comprising a relatively shallow bowl, of generally rhombic contour in top plan view, having blunt corners, and part-cover

members, the latter each having a generally segmental contour in plan and with an outwardly rounded contour in lines transverse to its line of connection with the tray or body portion and all of said members formed with peripheral edges leaving the top of the container open centrally and at its corners in the closed position of said members.

This application is a division of my prior pending application Serial No. D-58,050, filed August 9, 1935, now Design Patent 103,667.

What is claimed is:

The ornamental design for a display container or similar article, as shown and described.

ERNEST M. BROGDEN.

CERTIFICATE OF CORRECTION.

Design No. 109,048.

ERNEST M. BROGDEN.

It is hereby certified that the above numbered patent was erroneously issued to the inventor, said "Brogden" whereas said patent should have been issued to Bank of The Manhattan Company, Trustee, of New York, N. Y., a corporation of New York, as assignee of the entire interest in said invention, as shown by the record of assignments in this office; and that the said Letters Patent should be read with this correction therein that the same may conform to the record of the case in the Patent Office.

Signed and sealed this 10th day of May, A. D. 1938.
